UNITED STATES PATENT OFFICE.

CHARLES B. GILMORE, OF CHICAGO, ILLINOIS, ASSIGNOR TO CHICAGO FORGING & MANUFACTURING COMPANY, OF CHICAGO, ILLINOIS, A CORPORATION OF ILLINOIS.

HOOD LATCH.

Application filed March 24, 1928. Serial No. 96,938.

My invention relates to a fastening device and particularly to a device intended for use as an automobile hood latch. One object of the invention is to provide a device which will be used as a hood latch and which, while serving to hold the hood down and closed, will also force the hood inwardly against its abutment and will thus hold the hood against rattling. Another object is to provide a hood latch which operates independently of variations in position of the hood. Another object is to provide improved means for securing a spring in such a latch. Another object is to provide a hood latch having means for moving it, when released, out of the path of movement of the hood and for holding it, when released, at a predetermined position out of such line of movement. Other objects will appear from time to time in the course of the specification and claims.

My invention is illustrated more or less diagrammatically in the accompanying drawings wherein—

- 25 Figure 1 is an elevation of my latch showing it in position on the automobile;
 Figure 2 is a section on the line 2—2 of Figure 1;
 Figure 3 is a side elevation;
 Figure 4 is a top plan view;
 Figure 5 is a section on the line 5—5 of Figure 3;
 Figure 6 is a section on the line 6—6 of Figure 3;
 Figure 7 is a side view of a variant form;
 Figure 8 is a section on the line 8—8 of Figure 7; and
 Figure 9 is a perspective view of a part.

Like parts are designated by like symbols throughout the specification and drawings.

A is a portion of an automobile frame to which may be secured an upstanding rib or abutment member A¹, against which abuts the lower edge B¹ of the hood B, when the hood is closed. Fastened to the hood B is a member generally designated as B² which includes a downwardly and outwardly inclined cam portion B³, upwardly and outwardly inclined prongs B⁴ separated for example by the notch B⁵, a central securing portion B⁶ and a downwardly and inwardly

turned bottom portion B⁷. B⁸ are any suitable securing members.

C is any suitable shaft or pin terminating at the bottom in the squared head C¹, which may, but need not be integral. C² generally indicates a base member having the frame engaging securing portions C³, through which may pass any suitable securing members C⁴ and the intermediate raised portion 55 formed by the upwardly and inwardly inclined top member C⁵ and the generally vertical side walls C⁶. C⁷ is a downwardly concave generally spherical flange surrounding the aperture C⁸ through which passes the 60 pin C. C⁹ is an upwardly projecting flange along the inner edge of the top portion C⁵. The size of the aperture C⁸, in relation to the pin C and the head C¹ is such as to permit a considerable movement of the latch, 65 but to limit this movement to a predetermined maximum swing away from the closure, for example to the position shown in dotted line in Figure 3.

The latch body proper consists of the cylindrical member D herein shown as rolled from a single blank and with a single axial seam D¹. About the bottom of the cylinder are a plurality of ears D² adapted to be inwardly turned, as shown for example in 70 Figure 2 to engage and secure the washer D³ loose on the shaft C. Intermediate the ends of the cylinder, and preferably formed integral with it, is the outwardly projecting portion D⁴. The top of the cylinder may be 75 open but is provided with a rear abutment wall D⁵ and is cut away at the opposite side as at D⁶. D⁷ is a spiral spring adapted to be compressed between the washer D³ and an opposed washer or abutment D⁸ at the 80 top of the pin C.

E generally indicates a cam member adapted to engage the opposed cam member B³. The lower inwardly turned portion E¹ penetrates and is seated within a ledge or projection D⁴. The upper portion E² conforms to the inner side of the cylinder D and crosses its top, seating in the notch D⁵ and abutting against the wall D⁶. It is provided with downwardly turned ears E³ which 85 engage the inner face of the upper portion of the cylinder D, to which they may be spot 90 95 100

welded to hold the entire member E locked in position.

G generally indicates a handle member including the hand piece G¹ the intermediate portion G², and the T-shaped portion G³ the arms G⁴ of which are adapted to engage the inner sides of the fingers B⁴ when the T is positioned in the intermediate aperture B⁵ of the securing member B². G⁵ is any suitable securing means for securing the hand piece G to the upper portion of the member E.

Referring to Figures 7 and following, a variant form of securing member is employed including the frame engaging members H, the securing members H¹, the intermediate raised portion H² perforated at H³ and provided with vertical side walls H⁴. Interposed between the top portion H³ and the squared end C¹ of the pin is the rolling contact member H⁶, shown in detail in Figure 9, centrally apertured as at H⁷ provided with the upwardly convex transversely aligned rocking abutment members H⁸ and 25 the downwardly convex aligned rocking abutments H⁹ at right angles thereto. The upper top member H² is shown as horizontal but obviously it may if desired be upwardly and inwardly inclined. The cylindrical member D has a downwardly projecting lug K.

In the form indicated in Figure 7 in the place of the sheet metal cam portion E with a separate hand piece, I provide a unit casting generally indicated as J having the upper handle portion J¹, the finger piece J², the plug J³ adapted to penetrate the top of the cylinder D, the outwardly projecting T or hook portion J⁴, the intermediate portion J⁵, the upwardly and outwardly inclined cam portion J⁶ and the anchor portion J⁷ adapted to penetrate within the outwardly projecting member D⁴.

It will be realized that whereas I have described and shown a practical and operative device and several modifications thereof that many changes might be made in the size, shape, disposition and number of parts without departing from the spirit of my invention and that I wish my drawings to be taken as in a broad sense illustrative or diagrammatic rather than as limiting me to my specific showing herein.

The use and operation of my invention are as follows:

When the closure or hood is lowered into position with its lower edge abutting against the exterior of the flange A¹, I lift the latch against the pressure of the spring, engage the T with the hook on the closure, and release the latch. The engagement of the T and hook holds the latch in generally vertical position and prevents it from swinging outwardly away from the closure. The compression of the spring thrusts the cam

E on the latch against the downwardly and outwardly inclined cam blank on the hood and the result is a camming action which directs and maintains a pressure both downwardly and inwardly against the lower edge 70 of the closure. Thus the closure is not merely thrust downwardly toward the frame member A but inwardly against the abutment A¹.

When the hood or closure is to be released, the latch is raised by the operator, the locking cam portion E is lifted from engagement with the opposed cam member on the closure, and the T is removed from engagement with the hooks B⁴. When the latch is then released for downward movement along the pin C in response to the expansion of the spring D⁷, the lower edge of the member D engages the flange C⁹, in the form shown in Figures 1, 2 and 3 and 80 in response to the further expansion of the spring the latch is moved positively outwardly from the closure, to take the position shown in dotted line in Figure 3. Thus the spring D⁷ not only moves the latch positively 85 outwardly away from the closure, but holds it in a predetermined outward position, determined by the relative size of the aperture C⁸, the pin C and the head C¹.

It will thus appear that the latch is normally held withdrawn when the closure is released since the spring D⁷ is sufficient to hold the member D downwardly against the base member generally indicated as C² in Figures 1, 2 and 3, or the members H and the intermediate raised portion H² of Figures 7 and following. Obviously other means and shapes of opposed members may be employed to obtain the same effect, it being essential that the opposed bottom of the member D and the base portion to which it is opposed must be so shaped that the latch will swing outwardly in response to the expansion of the spring D⁷ or, if desired, in response to gravity, if a somewhat shorter 100 spring is used. Thus the release of the latch, after it has been withdrawn from holding connection with the closure, is sufficient to cause or permit the outward movement of the latch and the latch is held at 105 the outward limit of its movement, the location of its outward limit being determined, for example, by the size and form of the opposed parts.

Not only do I provide a simple and firm means for securing the hood in place, but I obtain positive freedom from rattling, because of the combined downward and inward thrust exerted as a result of the cam engagement.

In order to hold the latch normally withdrawn when the closure is released I position an upwardly projecting flange C⁹ on the base member C², or a downwardly depending member K on the latch cylinder, as 130

shown in Figure 7. Thus when the latch is released, the spiral spring thrusts it downwardly along the stem C and in either form the engagement of the member C⁹ or K with the base or the cylinder respectively is sufficient to cause the latch to fall outwardly away from the closure.

My latch is peculiarly easy to make and assemble since it is blanked out of a single blank, which is rolled into an open ended single seamed cylinder. I may employ simply applied handle and cam members either of strip stock or cast.

I have reduced to a minimum the friction between the stem and its bottom and the socket or base member about which it gyrates. Rotation of the stem is prevented, with a consequent reduction of friction and wear. I prefer to employ a rolling contact between the base member C² and the bottom C¹ of the stem C. By squaring the head C¹ and positioning it between the vertical walls C⁶ C⁸, I prevent the wear causing rotation. By leaving an aperture of sufficient cross section in the plate C⁵, I insure a range of gyration sufficient to permit the latch to be swung away from the closure or to swing longitudinally with the closure to compensate for longitudinal shifting of closure in relation to latch. The rolling contact may be obtained in a multiplicity of ways and I do not wish to be limited to the specific methods herein shown. However I find that one advantageous method is to provide a downwardly convex portion about the central aperture C⁸ of the plate C⁵. The stem can gyrate freely, and as it gyrates it rolls across such convex projection. In the form of Figure 7 I insert an additional wear taking member which has downwardly convex rolling portions H⁹ H¹⁰ along one plane and upwardly convex rolling portions H⁸ H¹⁰ along a plane at right angles thereto. The result is that no matter in what direction the stem may gyrate the wear and compression taking contact at the bottom of the stem is always a rolling or rocking contact as contrasted to a sliding contact.

A further effect of the use of the spring D⁷ is to draw the latch D downwardly either against the top of the pin C or against the stop C⁹ in such fashion as to reduce the ease with which the latch D can be rotated in relation to the pin C. The result is that the latch has a strong tendency to remain in the position in which it is set, so far as relates to the direction of the T lug toward the latch. This is of great convenience, in holding the finger piece or handle in the proper position for a direct lift upon the latch in order to drop the T lug between the members B⁴.

I claim:

1. In combination with a closure, a latch member, a stem upon which said latch mem-

ber is slidably mounted, a base upon which said stem is positioned adjacent said closure, yielding means normally thrusting said latch member downwardly toward said base, and a universal rolling connection between the bottom of the stem and said base.

2. In combination with a closure, a latch member, a stem upon which said latch member is slidably mounted, a base upon which said stem is positioned adjacent said closure, yielding means normally thrusting said latch member downwardly toward said base, a universal rolling connection between the bottom of the stem and said base, including in part a squared member at the bottom of said stem, a perforated plate through which the stem passes and a downwardly projecting convex portion about the perforation.

3. In combination with a closure, a latch member, a stem upon which said latch member is slidably mounted, a base member for said stem positioned adjacent said closure, yielding means normally thrusting said latch member downwardly toward said base member, and a universal rocking connection between said stem and said base member, said stem being held at all positions against rotation in relation to said base member.

4. In combination with a closure, a latch member, a stem upon which said latch member is slidably mounted, a base member for said stem positioned adjacent said closure, yielding means normally thrusting said latch member downwardly toward said base member, and a universal rocking connection between said stem and said base member, said stem being held against rotation in relation to said base member, including a perforated plate through which the stem passes, a downwardly projecting convex portion about such perforation, a squared laterally extended end portion on said stem, and wall members, associated with said plate and adapted to engage opposed edges of said squared portion.

5. In combination with a closure, a latch member, a stem upon which said latch member is slidably mounted, a base member for said stem positioned adjacent said closure, yielding means normally thrusting said latch member downwardly toward said base member, and a universal rocking connection between said stem and said base member, said stem being held against rotation in relation to said base member, including a perforated plate through which the stem passes, a squared laterally extended end portion on said stem, wall members, associated with said plate and adapted to engage opposed edges of said squared portion, and a rocking member interposed between said plate and said squared portion.

6. In combination with a closure, a latch member, a stem upon which said latch member is slidably mounted, a base member for said stem positioned adjacent said closure,

- yielding means normally thrusting said latch member downwardly toward said base member, a universal rocking connection between said stem and said base member, said stem being held against rotation in relation to said base member, including a perforated plate through which the stem passes, a squared laterally extended end portion on said stem, wall members, associated with said plate and adapted to engage opposed edges of said squared portion, and a rocking member interposed between said plate and said squared portion, said rocking member having upwardly convex portions lying along one plane and downwardly inclined portions lying along another plane at right angles thereto.
7. In combination with a closure, a latch member, a stem upon which said latch member is slidably mounted, a base member for said stem positioned adjacent said closure, yielding means normally thrusting said latch member downwardly toward said base member, and a universal rocking connection between said stem and said base member, adapted to permit a gyratory motion of the stem, and to prevent rotation of the stem about its axis.
8. In combination with a closure having an engageable portion, a fastener anchored adjacent said closure, a base member to which said fastener is anchored, the engaging portions of said base member and fastener being shaped to permit a gyratory motion and a rolling contact therebetween in any radial plane.
9. In an automobile hood latch, a stem and securing means for the bottom thereof, a latch movable along said stem, said latch including a tubular body portion, a spiral spring compressed between said stem and said body portion, and a closure engaging member secured to said body portion, said body portion being apertured intermediate its ends to receive the lower portion of said closure engaging member, the upper portion of said member being positively secured to the upper end of the tube.
10. In an automobile hood latch, a stem and securing means for the bottom thereof, a latch movable along said stem, said latch including a tubular body portion, a spiral spring compressed between said stem and said body portion, and a combined closure engaging and handle member secured to said body portion, said body portion being apertured intermediate its ends to receive the lower portion of said combined closure engaging and handle member, the upper portion thereof being positively secured adjacent the upper end of the tube.
11. In an automobile hood latch, a stem adapted to be positioned adjacent the hood, a base member for the bottom thereof, a latch member movable along said stem and

yielding means for normally thrusting it downwardly therealong, and a universal rolling contact between the bottom of the stem and the base member to which it is secured, including in part a downwardly convex portion associated with said base member and a laterally extended member, associated with said stem, in rolling contact therewith.

12. In an automobile hood latch, a stem adapted to be positioned adjacent the hood, a base member for the bottom thereof, a latch member movable along said stem and yielding means for normally thrusting it downwardly therealong, a universal rolling contact between the bottom of the stem and the base member to which it is secured, including in part a downwardly convex spherical portion associated with said base member, such base member being perforated concentrically with such spherical portion to permit the passage of said stem, and a laterally extended member, associated with said stem, in rolling contact with said spherical portion.

13. In an automobile hood latch, a stem adapted to be positioned adjacent the hood, a base member for the bottom thereof, a latch member movable along said stem and yielding means for normally thrusting it downwardly therealong, a universal rolling contact between the bottom of the stem and the base member to which it is secured, including in part a laterally extended member associated with said stem, the base member being perforated to permit the passage of said stem, and an intermediate member in rolling contact with the lower side of the base member and the upper side of said laterally extended member.

14. In combination with a closure, a latch for said closure, including in part an anchoring element associated with said latch, a base for said latch adjacent said closure and gyral rocking means intermediate said base and anchoring element.

15. In combination with a closure, a latch, a base member positioned adjacent said closure, means adapted to permit a limited gyratory movement of one end of said latch, and means adapted to provide a rocking connection between said latch and said base member in any plane of the gyration of said latch.

16. In combination with a closure, a latch, a base for said latch mounted adjacent said closure, a stem upon which said latch is rotatably mounted, a spring compressed between latch and stem, and a gyral rocking connection between said base and said stem.

17. In combination with a closure, a latch member mounted adjacent said closure, a gyral rocking supporting connection for said latch member, said latch member being adapted to direct a constant annular pres-

sure against the closure while in engagement therewith, and being adapted to permit a limited relative movement of closure and latch, during locking engagement.

- 5 18. In combination with a closure, a latch assembly including a latch member and a base to which it is secured, said base being mounted adjacent the closure, and means, including a spring associated directly with the latch assembly, adapted to withdraw said latch member, when released, outwardly from the closure and to hold it withdrawn, and means for limiting such withdrawal to a predetermined position.
- 10 19. In combination with a closure, a latch assembly including a latch member and a base to which it is secured, said base being mounted adjacent the closure, and means, including a spring associated directly with the latch assembly and an abutment member, between latch and base, adapted to withdraw said latch member, when released, outwardly

from the closure and to hold it withdrawn, and means for limiting such withdrawal to a predetermined position.

20. In combination with a closure, a latch assembly including a latch member and a base to which it is secured, said base being mounted adjacent the closure, and means, including a spring associated directly with the latch assembly, adapted to withdraw said latch member, when released, outwardly from the closure and to hold it withdrawn, the latch member and base being provided with opposed contacting surfaces adapted, in response to the action of said spring, to hold said latch in outwardly tilted position away from said closure and out of the normal line of movement thereof.

Signed at Chicago, county of Cook, and 46 State of Illinois, this 20th day of March, 1926.

CHARLES B. GILMORE.
